U.S. PATENT DOCUMENTS

We claim the ornamental design for a mount portion, as shown and described.

DESCRIPTION

1,538,758 A	5/1925	Taylor
1,703,649 A	8/1927	Weinstein
2,186,607 A *	1/1940	Judge et al. 248/343
2,870,985 A	1/1959	Martin et al.
3,440,331 A	4/1969	Cohen
3,574,340 A	4/1971	Busche
D221,634 S	8/1971	Bradspies et al.
4,239,196 A	12/1980	Hanger
D263,927 S *	4/1982	Dewey D8/399
4,533,127 A	8/1985	Hawkins
4,566,663 A	1/1986	Barchus
D286,147 S *	10/1986	Carlson D12/317
4,673,154 A	6/1987	Karapita
4,764,008 A	8/1988	Wren
5,037,267 A	8/1991	Warner et al.
5,139,223 A	8/1992	Sedighzadeh

FIG. 1 is a perspective view of a mount portion showing our new design;

FIG. 2 is a top view thereof;

FIG. 3 is a side view thereof;

FIG. 4 is a bottom view thereof;

FIG. 5 is a perspective view of another embodiment of the mount portion showing our new design;

FIG. 6 is a top view of the mount portion in FIG. 5;

FIG. 7 is a side view of the mount portion in FIG. 5; and,

FIG. 8 is a bottom view of the mount portion in FIG. 5.

The broken lines shown are for illustrative purposes only and form no part of the claimed design.
